(57) **CLAIM**

The ornamental design for a bottle holder, as shown and described.

DESCRIPTION

FIG. 1 is a perspective view of a bottle holder showing my new design;

FIG. 2 is a top front and right side perspective view of the bottle holder shown in a modified position;

FIG. 3 is a front view of the bottle holder, the back view being identical;

FIG. 4 is a right side view of the bottle holder, the left side being identical;

FIG. 5 is a bottom plan view thereof; and,

FIG. 6 is a top plan view thereof.

The broken lines shown the FIGS. are for illustrative purposes only and forms no part of the claimed design.
